UNITED STATES PATENT OFFICE.

ALEXANDER BLAKELY, OF FAIRFIELD, IOWA.

IMPROVEMENT IN RAILWAY-TRACK CLEANERS.

Specification forming part of Letters Patent No. 124,321, dated March 5, 1872.

Specification describing a new and useful Railroad-Track Cleaner, invented by ALEXANDER BLAKELY, of Fairfield, in the county of Jefferson and State of Iowa.

The invention will first be fully described, and then clearly pointed out in the claims.

Figure 1 is a side elevation of a locomotive, and Fig. 2 a side elevation of a track-cleaner.

A represents the boiler, and B the sand-box, having pipe b. This pipe extends down in front of the foremost driver C, and directly over the track. Whenever it is desired to increase the traction of the driving-wheels, the track is sanded; but when the wheels have passed over, it is desirable to remove this sand.

In Fig. 2, D represents the rear driver of a locomotive. E is a shaft, having a conical brush, e, at the front end and friction-roll e' at the other. This shaft is hung in bearings, so that the friction-roll e' will rest against the side of wheel D and be rotated thereby, while the brush e will rotate across the rail and sweep the sand off to one side. The mechanism which I preferably employ to hold this shaft E in position consists of the pivoted bearing-piece F and spring f, vibratory lever G and spring g, elbow-lever H and rod J, which connects with a lever within reach of the engineer in the cab, all arranged upon the side of the locomotive.

When the rod J, by means of its lever, is pulled back and held by a suitable detent, the elbow-lever H forces down the lever G, which raises the bearing-piece F and removes the friction-roller from the wheel. The spring f now draws up the brush-end of the shaft E from the rail. On the other hand, when the

track has been sanded in front of the drivers, the rod J and its operating-lever being released, the spring f throws down the shaft E, so that the friction-roll e' is brought into contact with wheel D. The latter carries upward the rubber roller by friction, the resistance of spring g is overcome, and the brush e is brought down upon the track. The roller e' rotates the shaft E and brush e until the former is removed from wheel. By this device, as soon as the sand has answered its purpose, it is easily swept from the track, while the device itself is readily suspended and out of the way when not in use.

Having thus described my invention, what I claim as new, and desire to secure by Letters Patent, is—

1. The shaft E, provided with a brush, e, at one end and a friction-roll, e', at the other, arranged on each side of the locomotive and in rear of hindmost drive-wheel, as described, so that the said shaft will be rotated by the drive-wheel, in the manner set forth.

2. The combination, with the said shaft E, having brush e and roll e', of the pivoted bearing-piece F, spring f, and lever G, as described, to enable the brush to be raised or lowered, and held to or away from the track, as set forth.

3. The subject-matter of second claim, in combination with the elbow-lever H, and connecting-rod J, all arranged as and for the purpose described.

ALEXANDER BLAKELY.
